GYROSCOPIC INTERNAL COMBUSTION
ENGINE

Pierce R. McCrary, Washington, D. C., assignor to
McCrary Engineering Company, Inc., a corpora-
tion of the District of Columbia

Application February 20, 1942, Serial No. 431,771

14 Claims. (Cl. 123—44)

The object of my invention is to provide a novel gyroscopic internal combustion engine of high efficiency mounted in a novel manner on a wheel, whereby it may be used to operate agricultural instruments, tanks and other vehicles at a minimum expense of construction and operation.

This invention relates to internal combustion engines and more particularly of the revolving type having a stationary crank although I am not limited to the stationary crank type, these new and novel features being applicable in whole or in part to any design of internal combustion engine, and to either carburetor or injected fuel types.

One of the objects in the above mentioned invention is to correct certain defects known to exist in engines of the above mentioned types and more especially in what is known as the 2-cycle construction.

Another object of this invention is to improve the general efficiency of such engines by the effective utilization of centrifugal force, and revaporization of unvaporized fuel after it has been taken into the engine housing, by applying centrifugal force in such a manner to effectually separate the unvaporized fuel from the vaporized fuel, and means for vaporizing the liquid thus separated both by air jet and by thermal reaction, thus securing a complete vaporization never before accomplished in an internal combustion engine, thereby attaining economy of operation and approximate perfect combustion and at the same time preventing the fouling of the spark plugs so objectionable in these types of engines.

It is an object of my invention to provide the system of centrifugal action and revaporization and control hereinafter described which contemplates the total elimination of all suspended matter in the fuel mixture and its conversion into hot vapor by the action of centrifugal force and three-state vaporization.

I attain these and other objects of my invention by the mechanism illustrated in the accompanying drawings, in which—

Figure 1 is a side elevation of the invention; Fig. 2 is a longitudinal section on a central line through my engine showing the fuel intake through the carburetor connection, a cut-off valve on the crank, a second-stage and third-stage vaporization means and also the transmission connection;

Fig. 3 is a longitudinal section on line 3—3 of Fig. 2, in the plane of the axis of an engine hav-

ing a single cylinder and pre-compression cylinder opposite the compression work cylinder;

Fig. 4 is a transverse section on line 4—4 of Fig. 3;

Fig. 5 is a transverse section on line 5—5 of Fig. 3;

Fig. 6 is a transverse section on line 6—6 of Fig. 3; and

Fig. 7 is a section on line 7—7 of Fig. 2.

Like characters of reference designate like parts in each of the several views.

The construction of the engine as shown is of the 2-cycle type, although I am not limited to this construction, and the revolving design as shown is of the single acting design consisting of only two moving parts, the cylinder wheel, and the double-headed piston.

Referring to the accompanying drawings, I provide a cylinder 1, a double-headed piston 2.

20 This piston is cross-slotted to carry a sleeve 26 on the crank pin 3', thus doing away with the connecting rod as we get the same relative crank action or power curve. However, I am not limited to this construction as a connecting rod and wrist pin may be used, if desired.

25 Crank shaft 3 is a stationary element rigidly connected to the chassis 32, and has its crank pin 3' offset from the center of the cylinder 1 and positioned in the transverse chamber 40 at the center of piston 1. The piston revolves with the cylinder wheel 24 and cylinder 1. The cylinder 1 is rigidly connected to the cylinder wheel 24 and revolves with but does not change its position relative to the cylinder wheel, as its axis is 30 that of the cylinder wheel while the axis of the piston is offset from that of the cylinder. Cylinder wheel 24 acts as control for gyroscopic torque.

35 The cylinder has a pre-compression chamber 4 at one end and a main compression or firing chamber 10 at the other end. A pipe 5 is mounted in the pre-compression end of the cylinder and extends longitudinally through the piston to the thermal vaporization chamber 8 in the piston.

40 It has orifices 6 through which fuel may enter from the pre-compression chamber 4 and pass to the vaporization chamber 8 in the piston. Pipe 5 functions both as a conduit for fuel and as a guide element to keep the cylinder in proper alignment with the piston. A deflector 7 is provided adjacent port 8' in the piston chamber 8 to prevent unvaporized fuel from passing into port 8' of the piston to the by-passes 9, which communicate with the main compression chamber 10.

45 50 55 The outer end of the piston 2 has a deflector

38 to prevent escape of fuel with the products of combustion through the cylinder exhaust port 33. The face of this deflector is curved as shown to effect the desired movement of the fuel entering the chamber 10. Fins 11 are provided in the piston, projecting into chamber 8 to function as a thermo-vaporizer in the head of the piston, as shown in Fig. 2.

Crank shaft 3 has a longitudinal channel 12 in communication with the carburetor connection 13. Channel 12 is plugged at its outer end. The crank shaft 3 has a radial extension 14 with its channel 15 positioned to communicate with the valve opening 16 (see Fig. 7), in a rotary valve 34. Valve 34 is mounted in a suitable recess in the piston, as shown in Fig. 2, and is affixed to or integral with the casting or hub element 17 of the cylinder wheel, as shown in Fig. 2. The sleeve valve 34 revolves with casting 17 to which it is affixed or with which it may be made integral. The opening 16 in sleeve valve 34 is intermittently in communication with fuel passage 15 and with chamber 8 and chamber 18 as the cylinder 1 and casting 17 which is bolted to cylinder 1 revolves around the crank shaft 3.

Fuel entering through the carburetor connection 13 and radial passage 15 enters chamber 18 in a partly vaporized state and passes through chamber 18 and extension passage 19 into the pre-compression chamber 4 where on the next half revolution of the cylinder wheel and cylinder the unvaporized portion is forced through pipe 5 to chamber 8 where the third stage of vaporization is effected by the heat of the piston head and fins 11, thence through the ports 8 and 9 into combustion chamber 10.

As shown in Figs. 2 and 3, a suitable sleeve or bushing 20 is provided for crank pin 3'. Chambers or spaces 21 are provided in the piston to reduce its weight. A hub element 22 is bolted to the cylinder 1 and keyed to or made integral with shaft 36. Shaft 36 revolves with the cylinder wheel. Brake 37 is keyed to member 27 to which one of the gears is also keyed, the ratio of the gears depending on the relative number of teeth.

Combined hub and transmission casing 23' with the spokes 23 revolve on shaft 36 on one side of the cylinder and hub members 23'' revolve on crank shaft 3 on the other side of the cylinder. Spokes 23 are affixed to spoke extensions 25, to which in turn the traction wheel 26 is secured, as shown in Figs. 1 and 2. The cylinder 1 is affixed to cylinder wheel 24, as shown in Figs. 1 and 3.

Keyed on member 27 is one of the transmission gears 28 contained within the transmission casing 29 and 23' and functioning to modify or increase the speed of rotation of members 29 and 23' relative to that of the cylinder wheel 24 and traction wheel 26. Hub members 22 are keyed to shaft 36, on which spoke hubs 23', spokes 23 and spoke extensions 25 revolve.

For starting the engine, a conventional spark plug 31 is provided, as shown in Fig. 3, to which a wire 30 is connected and which is run through a suitable channel in shaft 36 and thence to the spark plug in any suitable manner.

I may provide any suitable chassis 32 on which the cylinder wheel and engine are mounted and I may provide either a single engine cylinder or any suitable number of cylinders for the wheel or wheels carrying the chassis.

The compression or firing chamber 10 has an exhaust port 33, as shown in Fig. 3, opposite

ports 8. The deflector 38 on the end of the piston has a curved face. This deflector has an important function in blowing expanded gases out of the chamber 10 to help scavenge the engine.

The operation of the engine is as follows: When the cylinder wheel 24 and cylinder 1 revolve, the sleeve valve 34 revolves with the cylinder and covers and uncovers the fuel passage 15 at the proper time in rotation. The fuel mixture is drawn into the crank shaft channel 12 through the carburetor connection 13, and passes through channel 15, and port 16 of valve 34 into either the piston thermal vaporizing chamber 8 or successively into the pre-compression chamber 4 through the pipe 5 at the opposite end of the revolving piston and cylinder. The unvaporized fuel in chamber 4 is then forced by air pressure by the compression end of the piston reducing the space of chamber 4 and forcing fuel up through pipe 5 and into the piston thermal vaporizing chamber 8.

Chamber 8 has a series of inwardly projecting fins 11 for radiating heat from the piston head and thereby further vaporizing the fuel mixture. Ports 8' of chamber 8 and by-passes 9 from ports 8' to firing chamber 10 will at the proper time connect the chamber 8 with the firing chamber 10, whereby the latter will receive the vaporized fuel, and as the size of chamber 10 is reduced will compress the charge, and ignition will be accomplished in the conventional manner by electric ignition to start the engine.

One novel feature of the engine is the bringing of the cool vaporized fuel up through the hollow piston. The curved face of the deflector 7 in the piston chamber 8 will cause the mixture of vaporized and unvaporized fuel to flow up into the head of the piston cooling the piston head. In turn the gases become heated, thus assisting in heat exchange, and thereby attaining a better and more complete combustion of the fuel, and at the same time preventing the fouling of the spark plugs.

Hollow tube 5 performs two functions, namely, it acts as a guide to prevent the oscillation or twisting of the piston 2 caused by the action of the crank pin 3 and at the same time carries the air jet of fuel to the opposite end of the piston and into the thermal vaporizer chamber 8.

Member 22 is bolted to and moves with cylinder 1. It is also keyed to gears 28 through which the hub members and members 29 and 23' are caused to revolve, when brake 37 is applied. One of the gears 28, and the brake 37 are keyed to member 27 and the shaft 36 is keyed to or integral with member 22.

The channelled crank shaft 14 is rigidly secured to chassis 32 and does not revolve. All members 39 are washers to exclude dirt, and oil or grease retainers. 39' is a key on driving gear 41 securing it to shaft 36.

This engine is believed to be especially adapted to advantageous use with the heavier than gas fuels, such as fuel oil, in what is known as the semi-Diesel type of engine, where there is a tendency to precipitation, the consequence being that a relatively small portion of the fuel is carried in the form of vapor to the combustion chamber.

It is believed that the construction of my internal combustion engine herein described will prove highly efficient when using a not easily inflammable fuel; that it will substantially reduce the fire hazard; and that it will also reduce the

cost of manufacture and the cost of operation in all classes of internal combustion engines.

What I claim is:

1. In an internal combustion engine, the combination of a wheel, an engine mounted on and revolving within the wheel, a stationary channel crank shaft through which the fuel mixture is supplied, an offset stationary crank pin integral with the crank, a revolving sleeve on the crank pin, a piston mounted on the crank pin and having its center portion offset from the center of the wheel.

2. In an internal combustion engine of the type described, the combination of a stationary crank shaft, a cylinder revolvably mounted on the stationary crank shaft, a stationary offset crank pin, a revolving sleeve on the crank pin, a piston having its approximate central portion mounted on the crank pin whereby to cause the cylinder to revolve around the stationary crank shaft and the piston to revolve around the stationary offset crank pin.

3. In combination with the mechanism defined in claim 2, a rotary valve having its valve passage alternately opened and closed by the revolving of the cylinder.

4. In an internal combustion engine, the combination of a cylinder mounted for revolution on its central axis, a piston mounted for revolution on an axis central of the piston but offset from the central axis of the cylinder, a crank having its crank pin positioned at the central axis of the piston, a firing chamber at one end of the cylinder and a precompression chamber at the other end of the cylinder for collecting unvaporized fuel, a pipe extending longitudinally through the piston providing a passage for unvaporized fuel from the aforesaid pre-compression chamber to the vaporizing chamber with the head of the piston for further vaporization of the fuel.

5. In an internal combustion engine, the combination of a cylinder mounted for revolution on its central axis, a piston mounted for revolution on an axis central of the piston but offset from the central axis of the cylinder, a crank having its crank pin positioned at the central axis of the piston, a firing chamber at one end of the cylinder and a pre-compression chamber at the other end of the cylinder for collecting unvaporized fuel, a pipe extending longitudinally through the piston providing a passage for unvaporized fuel from the aforesaid pre-compression chamber to the vaporizing chamber within the head of the piston for further vaporization of the fuel, ports opening out of said vaporizing chamber in the piston head and by-passes extending from said ports, and a main compression chamber with which said by-passes connect while the main compression chamber is at its most expanded size.

6. In combination with the mechanism defined in claim 5, a deflector positioned on the end of the cylinder, said deflector having an inwardly curved face, a cylinder and also an exhaust port positioned oppositely from the curved face of the deflector.

7. In an internal combustion engine of the type described, the combination of a cylinder, a cylinder wheel in which the cylinder is mounted, a piston mounted in the cylinder and having its axis offset from the axis of the cylinder, a stationary crank having its crank pin projecting into the axis of the piston, a revoluble sleeve on said crank pin, a piston having a double head, a precompression chamber for collecting unvaporized fuel at

one end of the piston, a firing chamber in the cylinder at the other end, a tube extending longitudinally through the piston from the pre-compression chamber, a thermal vaporization chamber in the firing end of the piston in which said tube terminates, and inwardly projecting fins extending from the head of the piston into the said chamber to vaporize the fuel.

8. In an internal combustion engine of the type described, the combination of a cylinder, a cylinder wheel in which the cylinder is mounted, a piston mounted in the cylinder and having its axis offset from the axis of the cylinder, a stationary crank having its crank pin projecting into the axis of the piston, a revoluble sleeve on said crank pin, a piston having a double head, a pre-compression chamber for collecting unvaporized fuel at one end of the piston, a firing chamber in the cylinder at the other end, a tube extending longitudinally through the piston from the pre-compression chamber, a thermal vaporization chamber in the firing end of the piston in which said tube terminates, inwardly projecting fins extending from the head of the piston into the said chamber to vaporize the fuel, ports opening out of said chamber, an inwardly projecting deflector positioned in front of said port, ports connected with said ports, and a main compression chamber with which said ports communicate.

9. In combination with the mechanism defined in claim 8, a deflector on the head of said piston, said deflector having a curved face disposed opposite said by-passes, a cylinder having an exhaust port on the opposite side from the ports opening into the firing chamber.

10. In an internal combustion engine of the type described, the combination of a cylinder, a piston mounted in the cylinder, said piston having an internal vaporization chamber, a tube extending longitudinally through the piston for conducting fuel into said chamber, a port opening out of said chamber, and a deflector for preventing unvaporized fuel from going directly from said chamber into the firing chamber.

11. In an internal combustion engine of the type described, the combination of a cylinder, a double headed piston mounted in said cylinder and having its axis offset from the axis of the cylinder, a pre-compression chamber at one end of the cylinder, a firing chamber at the other end of the cylinder, a tube extending through the piston from the pre-compression chamber, a vaporization chamber within the piston head into which said tube discharges its fuel, a deflector for preventing unvaporized fuel from leaving said chamber, said chamber having inwardly projecting fins to function as a thermal vaporizer.

12. In an internal combustion engine of the type described, the combination of a cylinder, a double headed piston having its axis offset from the axis of the cylinder, a pre-compression chamber at one end of the cylinder and a firing chamber at the other end of the cylinder, a thermal vaporizing chamber within the piston head, a tube extending from the pre-compression chamber to the thermal vaporizing chamber, a port adapted to be put into and out of communication with the thermal vaporizing chamber of the piston and connecting with the firing chamber, an exhaust port opening out of the firing chamber, a deflector on the piston head having a curved face disposed opposite the portion of the by-pass which connects with the firing chamber, a hollow crank shaft in communication with

the carburetor, said crank shaft lying in the plane of the axis of the cylinder, said crank shaft having an offset crank pin lying in the plane of the axis of the piston, said crank pin having a revoluble sleeve in contact with the piston, and passages through the piston for vapors of the fuel mixture to the pre-compression chamber at one end of the piston and to the thermal vaporizing chamber within the head of the piston, substantially as and for the purposes described.

13. In an internal combustion engine having one or more cylinders, means for supplying fuel in a stream including vaporized and unvaporized fuel phase, centrifugal means for separating the

unvaporized from the vaporized phase after the stream is in the engine cylinder or cylinders, means having a pocket for receiving unvaporized fuel, means for vaporizing the unvaporized fuel, and means for causing the vaporized fuel to flow into the combustion chamber.

14. In an internal combustion engine, an external carburetor for vaporizing fuel, centrifugal action for separating unvaporized fuel from the vaporized fuel, an air jet for vaporizing the unvaporized fuel, a thermal vaporizer for more fully vaporizing the fuel, and a pocket for retaining the unvaporized fuel.

PIERCE R. McCRARY.
